U.S. PATENT DOCUMENTS

1,454,280 A 5/1923 Henrikson
1,982,538 A 11/1934 Reedy

DESCRIPTION

FIG. 1 is a top perspective view of a faucet according to an exemplary embodiment;

FIG. 2 is a left-side elevation view of the faucet of FIG. 1;

FIG. 3 is a front elevation view of the faucet of FIG. 1;

FIG. 4 is a rear elevation view of the faucet of FIG. 1;

FIG. 5 is a top plan view of the faucet of FIG. 1; and,

FIG. 6 is a bottom plan view of the faucet of FIG. 1.

The ornamental design which is claimed is shown in solid lines in the drawings. The broken lines in the drawings are for illustrative purposes only and form no part of the claimed design.

1 Claim, 2 Drawing Sheets
